UNITED STATES PATENT OFFICE

96,190

DESIGN FOR CRINKLED TINSEL

Philip Kranz, Philadelphia, and Adolph Hartmann, Elkins Park, Pa., assignors to Bernard Wilmsen, Philadelphia, Pa.

Application December 28, 1934, Serial No. 54,634

Term of patent 14 years

To all whom it may concern:

Be it known that Philip Kranz and Adolph Hartmann, citizens of the United States, and residents of Philadelphia, in the county of Philadelphia and State of Pennsylvania; and Elkins Park, in the county of Montgomery and State of Pennsylvania, respectively, have invented a new, original, and ornamental Design for Crinkled Tinsel, of which the following is a specification.

In the accompanying drawing Fig. 1 represents a plan view of the crinkled tinsel showing our design, the same being enlarged about four times the natural size.

Fig. 2 represents a side elevational view of Fig. 1.
Fig. 3 represents a section on line 3—3 of Fig. 1.

Fig. 4 represents a section on line 4—4 of Fig. 3.
Fig. 5 represents a section on line 5—5 of Fig. 3.

The drawing is as near a representation of the actual appearance of the tinsel as can be had with pen and ink, but we wish to point out that the dominant features of our design consist in a central row of generally prismatic or pyramidal light reflecting surfaces and crinkled marginal or border areas which are continuations of and merge with said central row.

We claim:

The ornamental design for crinkled tinsel as shown and described.

PHILIP KRANZ.
ADOLPH HARTMANN.
